I. Keller,

Sawing Machine.

No. 91,544.

Patented June 22, 1869.

United States Patent Office.

ISAAC KELLER, OF RANDOLPH, OHIO.

Letters Patent No. 91,544, dated June 22, 1869.

IMPROVEMENT IN WOOD-SAWING MACHINES.

The Schedule referred to in these Letters Patent and making part of the same.

To all whom it may concern:

Be it known that I, ISAAC KELLER, of Randolph, in the county of Portage, and State of Ohio, have invented new and useful Improvements in Sawing-Machines; and I do hereby declare that the following is a full, clear, and exact description of my invention, reference being had to the accompanying drawings, forming a part of this specification, and to the letters of reference marked thereon, of which drawings—

Figure 1 is a side view of my improved sawing-machine.

Figure 2 is a plan of the same.

Figure 3 is a detail section, showing the arrangement of the shaft, sliding collar, and guide-collar.

Figure 4 is a section made by plane 1 2 of plan.

Figure 5 is a detail view of mechanism for raising and lowering the saw.

Figure 6 is a detail view of rotary-saw-bar guides and post for supporting the reverse-lever.

Figure 7 is a sectional view of a rotary-saw-bar guide.

My invention relates to that class of sawing-machines known as "crosscut-sawing machines," and consists in the peculiar mechanism for working logs backward and forward, without interfering with the operation of the balance of the machinery, whereby I obtain a more perfect mechanical control of the log, and am better able to bring it into exactly the position required; also in the peculiar arrangement of the saw-bar, slides, guides, and connecting-rod, or pitman, whereby I obtain an easy movement of the saw, both in sawing and in raising the saw after the log has been sawed, and avoid any unnecessary friction or weight in any of the parts; and, lastly, in the peculiar arrangement of levers for holding the log while being sawed, whereby I obtain a simple device which is sure in its operation, easy to adjust to any size of log, and which is readily disengaged when the log is to be moved.

To enable others skilled in the art to make and use my invention, I will proceed to describe its construction and operation.

The principal frame of the machine is shown at A, and is made of wood or any suitable material, in general form, as shown.

The main shaft B is arranged in boxes on the frame A, as shown, and receives the power, through the universal joint D, from the driving-shaft C, which is driven by horse-power or in any other suitable manner.

The shaft H is hung in boxes on the frame A, directly above the shaft B, and carries the fly-wheel I, which has a crank-pin, J, to which the connecting-rod L is attached.

The gear-wheel E is hung on the shaft B, and is free to turn on said shaft.

The gear-wheel G is fixed on the shaft H, and meshes into the wheel E.

A sliding collar, F, is arranged on the shaft B, and has around it a guide-collar, u, which is attached to the lever Q.

A slot, t, is cut in the shaft B, and a projection, t, is made on the inside of the collar F, which causes said collar to revolve with the shaft B, as is fully shown in fig. 3.

The collar F and gear-wheel E are arranged with suitable teeth, so as to clutch and revolve together when brought up to each other.

It is readily seen, that by moving the end of the lever Q, which is pivoted to the frame A by a pin, a, and rests over the arm of post v, the fly-wheel I may be thrown in or out of gear with the driving-shaft B by the action of the collar F, as shown.

The long frame A¹ is attached to the frame A, and to the carriage-way A² A², as shown, and connects them together.

The post v is inserted in the frame A¹, and on this post are arranged the rotary guides q q, as shown, which guide and support the slides Y Y, as shown in figs. 1 and 2.

The saw-bar Z is secured between the ends of the slides Y Y, and passes forward through the rest r, and has the saw c at its front end. The connecting-rod L is pivoted between the slides Y Y, and connected to the crank-pin J, as shown, from which it is easily seen that the rotation of the fly-wheel I causes a reciprocating movement of the saw c.

The saw-bar rest r works up and down in the guide-posts s s, which are inserted in the frame A¹, and is operated by the lever o, arranged as shown, to which it is attached by the rod n.

The toothed iron, p, is arranged at the end of the lever o, and serves to support said lever in any desired position by hooking over a pin at the top of the guide-post s, as shown.

A roller, m, is inserted in the upper part of the saw-bar rest r, as shown, and serves, by rolling on the upper face of the saw-bar, which, when in operation, is supported by the rotary guides q q, and by the saw c, working on the log, to carry the weight of the rest r, rod n, iron, p, and end of lever o, without causing much friction on the saw-bar Z.

A pin, w, is inserted in the guide-post s, which prevents the saw from falling, and being broken, when the cut through the log is made.

The front end of the log which is to be sawed rests on the feed-roller X, and the rear end is supported by a carriage, d, which runs on the carriage-way A² A², and which is seen, in side view, at d'.

The feed-roller X is connected, by the universal joint W, to the rod V, which is connected, by a universal joint, U, to the gear-wheel T, which is hung on a suitable axis attached to the frame A.

This gear-wheel T meshes into the gear-wheel S,

which is fixed on the shaft R, which has the bevel-gear wheel M on the opposite end, and is arranged in boxes on the frame A, as shown.

The bevel-gear wheel M meshes into the bevel-gear wheels O O, which are hung on the shaft B, and are free to turn thereon.

The sliding collar N, which is operated by lever P, is made and arranged in a similar manner to the collar F, shown in fig. 3, and has teeth at both ends, which couple with corresponding teeth on the wheels O O when the collar N is brought up to said wheels. It is easily seen, that by means of the lever P, the collar N may be brought up to either of the wheels O O, and that in this manner the log may be moved forward or back at pleasure.

A lever, f, is pivoted, at y, to a bar which connects the frame A and post v, as shown, and extends down over the log, and has a point, or brad, g, which is so situated as to be forced into the log when any pressure is exerted on it.

A lever, k, is attached, at one end, to the side of the carriage-way A², and has arranged, in it, the iron, l, which has holes therein, and which passes through a hole in the lever f, and is secured at any desired point in said lever by a pin passing through the lever and one of the holes in the iron, l.

A ratchet, i, is attached to the lever f, and a catch, z, is attached to the lever k.

It is easily seen, that when the log is brought to the proper place, and the iron, l, secured in the proper position, by pressing down the lever k, the brad g will be forced into the log, and then, when the catch z on the lever k is fastened in the ratchet i, the log will be firmly held on the feed-roller and carriage while being sawed. When the log is to be moved, the catch z on the lever k is disengaged from the ratchet i, and the

lever k is then raised, which pulls the brad g out of the log, and leaves the log free to move.

I am aware that a combination of fixed and loose gear-wheels, rods, sliding clutch-collar, spring, and lever, has been before shown in a sawing-machine, in which the spring acts to hold the clutch-collar in an intermediate position between the loose gear-wheels, the whole combination serving to produce a backward and forward movement of the log, and I, therefore, lay no claim to my combination of parts for effecting this movement of the log when a spring is used in combination with the clutch-collar, as described; but

What I do claim as my invention, and desire to secure by Letters Patent, is—

1. The combination of the shaft B, loose bevel-gear wheels O O, sliding clutch-collar N, bevel-gear wheel M, shaft R, gear S T, universal joints U and W, rod V, and feed-roller X, the several parts being arranged as and for the purpose herein specified.

2. The arrangement of the connecting-rod L, slides Y Y, united, by a heck, at their centres, as shown,) saw-bar Z, oscillating guides q q, and post v, when the several parts are constructed, arranged, and operated in the manner and for the purpose specified.

3. The arrangement of the lever f of the third order, provided with brad g and ratchet i, the connecting and adjusting-iron l, the working-lever k, with catch z and the carriage-way A², when the several parts are constructed and operated in the manner and for the purpose set forth.

As evidence that I claim the foregoing, I have hereunto set my hand, in the presence of two witnesses, this 18th day of February, 1868.

Witnesses: JOHN F. KELLER, ISAA� KELLER.
MARION HUFFMAN.
